UNITED STATES PATENT OFFICE.

LEANDER K. DUTTON, OF OSKALOOSA, IOWA.

WASHING-MACHINE.

SPECIFICATION forming part of Letters Patent No. 313,407, dated March 3, 1885.

Application filed January 31, 1884. (No model.)

To all whom it may concern:

Be it known that I, LEANDER K. DUTTON, a citizen of the United States, residing at Oskaloosa, in the county of Mahaska and State of

5 Iowa, have invented certain new and useful Improvements in Washing-Machines; and I do declare the following to be a full, clear, and exact description of the invention, such as will enable others skilled in the art to which it 10 appertains to make and use the same, reference being had to the accompanying drawings, and to letters or figures of reference marked thereon, which form a part of this specification.

Figure 1 of the drawings is a vertical sectional view of my device, and Fig. 2 is a longitudinal sectional view of the same.

This invention has relation to washing-machines; and it consists in the construction and novel arrangement of the zinc bottom-plate, 20 stamped with alternate sector-shaped series of corrugations tapering toward the center, and smooth sector-shaped intervals; and of the corrugated zinc rubbers on the sides of the box or tub, having each a dovetail recess to receive 25 the body of a brush located in the middle of the rubber, all as hereinafter set forth.

In the accompanying drawings, the letter A designates the box or tub, having the bottom B and side walls, C.

30 D is the top through which passes the vertical pinion-shaft.

E represents the zinc bottom-plate, which is designed to be cut usually a little smaller than the bottom of the tub, a marginal interval of an inch or more being left, so that the plate may be nailed or screwed to the bottom B with facility, and so that it will be perfectly flat, and without wrinkles. The plate E is pressed or stamped to provide sector-shaped 35 series F of corrugations G, which alternate with sector-shaped smooth intervals H, these corrugated places and smooth places being radially arranged about a smooth center, K.

The corrugations G are radial and taper from 40 their outer ends toward the center, as shown. The plate is made in this form so that the clothes or articles being washed will, as they are carried around in the water by the pins of

45 the stirrer, be alternately operated upon by the rubbers and relaxed, the loosening or relaxation being designed to allow the clothes to fall at intervals, so as to bring them into more

intimate engagement with the rubbing corrugations, and to change their position somewhat as they pass from one series of corruga- 55 tions to another.

L indicate the side rubbers, usually three in number, arranged upon three sides of the box or tub. Each rubber consists of a strip of zinc, having on each side corrugations m, extending vertically, and between these a central longitudinal recess, n, of dovetail form, adapted to receive and hold a brush, P, which projects beyond the plate. The body of this brush (indicated at r) is made in dovetail form, 65 so that it can be easily passed into the dovetail channel or recess n of the plate, and readily withdrawn therefrom when necessary. A strip or stop-piece, s, nailed or screwed to the box, is sufficient to hold the brush down, and 70 can be readily taken off when it is desired to remove the brush. The side edges, t, of the plate L are bent backward and engage vertical gains v in the tub-wall. These side flanges, t, and gains are usually sufficient to hold the 75 plates, the central channel abutting against the wall.

N represents the vertical pinion-shaft, upon the lower end of which is applied the triple-armed stirrer-frame Z, which is made with a 80 central eye or hub, w, and is secured to the shaft by means of a nut, a, applied to the threaded lower end of the shaft. Each arm b of the stirrer-frame is formed with a deep socket, c, at its end, opening downward and serving to receive the tang d of the pin V, which extends downward into the tub, and is designed to engage the clothes and carry them around when the shaft is turned. Usually the upper end of each socket c is provided with 85 an aperture, e, through which a threaded extremity, g, of the tang d projects, and a nut, h, is applied thereon to hold the pin securely in 90 position.

The pins V may be made smooth and tapering, or in other common form; but it is preferred to make them in flattened tapering form, and with a longitudinal opening or slot, z, extending from a short distance below the shoulder k to near the lower end, l. These link- 95 form pins are designed to be very durable and very effective in their operation.

The frame Z and the pins are designed to be made of malleable iron and galvanized.

When the pins are made of wood, the arm-
sockets are made open at top, and the ends of
the pins are secured therein by wedging a
small piece of wood in a cleft made in the top
5 of the pin.

The hub of the metallic stirrer-frame is pro-
vided with an annular flange extending down-
ward from its under side, forming a recess
deep enough to receive the nut which secures
10 the frame to the shaft. This annular flange
a' serves as a guard to prevent the clothes in
the tub from coming in contact with the nut
in such a manner as to be injured.

Having described this invention, what I
15 claim, and desire to secure by Letters Patent,
is—

1. The zinc bottom formed from a single
plate having stamped therein alternate sector-
shaped series of corrugations tapering toward
20 the center, and smooth sector-shaped inter-
vals, substantially as specified.

2. The combination of the corrugated zinc
side rubber having a central vertical dovetail

recess and adapted to be secured to a tub, and
the brush having a dovetail body, substan- 25
tially as specified.

3. The combination, with a corrugated zinc
side rubber having lateral marginal flanges
extending backward, and a central dovetail
recess, of the detachable brush having a body 30
of dovetail form, and the tub having the ver-
tical gains, substantially as specified.

4. As an organized element of machines of
the character set forth, the corrugated zinc
rubber having a central dovetail recess, with 35
the vertical corrugations on opposite sides
thereof, and their ends bent backwardly to be
secured in the side walls of a tub, substantially
as specified.

In testimony whereof I affix my signature in 40
presence of two witnesses.

LEANDER K. DUTTON.
